UNITED STATES PATENT OFFICE

2,211,031

REINFORCED SPINDLE

John F. Schylander, Chicago, Ill.

Application January 3, 1938, Serial No. 183,241

4 Claims. (Cl. 242—68)

The invention relates generally to spindle caps, and more particularly to reinforced caps for spindles used in duplicating machines or the like. The invention has among its objects the production of a spindle cap which is simple in construction, inexpensive to manufacture, durable, and satisfactory for the purpose intended.

Another object of the invention is the production of a cap which is reinforced, and which may be adapted to various types of spindles, either of wood, metal or other material, solid or of tubular form.

Many other objects and advantages of the construction herein shown and described will be obvious to those skilled in the art from the disclosure herein given.

To this end, my invention consists in the novel construction, arrangement and combination of parts herein shown and described and more particularly pointed out in the claims.

In the drawing wherein like reference characters indicate like or corresponding parts:

Fig. 1 is a plan view of a spindle embodying my invention;

Fig. 2 is an enlarged elevational view of the end of the spindle shown in Fig. 1;

Fig. 3 is an enlarged sectional view taken on the line 3—3 of Fig. 2; and

Fig. 4 is an enlarged sectional view taken on the line 4—4 of Fig. 2.

Referring to the drawing, and more particularly to Figs. 1 and 2, 1 represents a spindle similar to that used in duplicating and other machines, which for illustrative purposes is shown as constructed of wood. My device, however, would be used equally as well in conjunction with a spindle of metal, Bakelite or other material, either of solid or tubular construction.

The end member, designated generally by the numeral 2 and preferably a stamping, comprises a bottom 3 with the side walls 4 and 5 extending therefrom to form a channel or groove 6 which is adapted to receive the means for supporting the spindle, as for example, a lug 7, indicated in dotted lines. Extending outwardly from the side walls 4 and 5, are face portions 8 and 9, respectively, adapted to overlie the end of the spindle. To readily obtain proper alignment and engagement between the spindle and supporting means, the face portions 8 and 9 are provided with inclined or concave surfaces 10 and 11, respectively, adjacent the groove or channel 6, said surfaces tending to guide the supporting means into said groove. These concave surfaces terminate in the

shoulders 12 and 13 which are spaced from the corresponding edges 14 and 15 of the member, the intermediate portions between a shoulder and corresponding edge being substantially flat.

A retaining ring 16 is provided to maintain the end member 2 in proper position on the spindle. This ring is provided with the internal flange 17 adapted to overlie that portion of the end member intermediate the shoulders 12 and 13, and the edges 14 and 15, respectively. The inner edge 18 of the flange engages the shoulders 12 and 13, thus preventing any relative lateral movement between the members or any spreading of the side walls 4 and 5 to provide a reinforced spindle cap. The hole 19 is provided merely as an aid in centering the material on a forming machine in the course of construction.

The end of the spindle 1 is provided with a recess 20 and a groove or channel 21 of a size to receive said end member, the groove 21 preferably closely engaging the side walls 4 and 5. If a tubular spindle is used, the side walls are notched to receive and closely engage the side walls 4 and 5 similar to the solid spindle. In either case, the face portion intermediate the shoulders and edges can be made to seat on the end of the spindle. The cap 16 is then placed in position on the spindle, the flange engaging the shoulders, as previously described.

As shown, the outer diameter of the retaining ring or cap 16 is preferably the same as that of the spindle, the diameter of that portion of the spindle underlying the ring being substantially the same as the inner diameter of the ring, thus forming a neat and trim spindle, as well as eliminating any projecting edges or corners.

Indentations 22 or other means may be provided, if desired, to insure the cap or ring 16 being securely held on the spindle, instead of relying solely on the frictional engagement of the parts.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A two-piece spindle cap of the kind described comprising an end member consisting of a bottom, side walls extending therefrom, and face

55

portions extending outwardly from and transversely to said walls, a retaining member partially overlying said face portions and means on said face portions engaging said retaining member for preventing spreading of the side walls and face portions.

2. A spindle cap of the kind described comprising a concave end member having a recess therein, a shoulder extending from the face of said member and spaced from the periphery thereof, a retaining member adapted to overlie the periphery of the face of said end member and engage said shoulder.

3. In a spindle cap of the kind described, a concave end member having a lateral slot across

its face, a shoulder extending from the face of said member but spaced from the periphery thereof and a retaining member adapted to overlie said face intermediate the periphery thereof and the shoulder, and engage the latter.

4. A spindle of suitable material notched at an end, a plate positioned on the end of the spindle and having an offset portion seated in said notch, a retaining member overlying a portion of said plate and flanged to overlie the sides of the spindle, and means on said plate spaced from the periphery thereof engaging said retaining member for preventing spreading of the plate at the offset portion in the spindle notch.

JOHN F. SCHYLANDER. 15
